Primary Examiner — Sandra Snapp*Assistant Examiner* — Ieisha N Price(74) *Attorney, Agent, or Firm* — Richard A. Fagin(57) **CLAIM**

I claim the ornamental design for an extrusion, as shown and described.

DESCRIPTION

FIG. 1 is an above front perspective view of an extrusion showing my new design;

FIG. 2 is a below rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is an underneath view thereof.

The extrusion is shown with a symbolic break in its length, which break is rendered in dot-dot-dash broken lines. The appearance of any portion of the article between the break lines forms no part of the claimed design. The dot-dot-dash broken lines in the drawings define the bounds of the claim and form no part of the claimed design.
